BY Wm F. Friedenreich

Atty

UNITED STATES PATENT OFFICE

FLOYD SMITH, OF MORRISVILLE, PENNSYLVANIA, ASSIGNOR TO SWITLIK MANUFACTURING COMPANY, A CORPORATION OF NEW JERSEY

PARACHUTE HARNESS

Application filed November 4, 1939. Serial No. 404,556.

The present invention relates to harnesses intended to support a rider from a parachute, and it has for its object to produce a harness that shall be simpler, better and safer than prior harnesses.

When a rider wearing one of the harnesses now in general use falls backward or head down, the side pull of the lifting webs or suspension elements loosens the breast straps, so that the harness is drawn off the shoulders and the rider can fall out. Viewed in one of its aspects, my invention may be said to have for its object to produce a simple and novel harness that shall securely hold the rider regardless of the manner in which he jumps or falls.

Another objection to the type of harness now in use is that the strain on the back straps tends to pull the strap seat out from under the rider, causing the weight of the rider to be transferred to the leg straps.

When this occurs, the rider is not only very uncomfortable but is sometimes injured. Viewed in another aspect my invention may be said to have for its object to produce an efficient harness in which there shall be no back pull on the strap seat, whereby the latter will always maintain its proper position effectively to perform its intended function.

Harnesses must be capable of being adjusted to persons of various sizes, and my invention has for one of its objects to produce a novel construction whereby a harness may be quickly and easily adjusted and will always be comfortable and safe regardless of the size of the person to whom it is adjusted.

While the rider should be tightly held during a descent, a tightly fitting harness on a person sitting down is uncomfortable. A further object of my invention is to produce a harness that will be safely tight when the wearer is standing but comfortably loose when he is sitting down.

In manufacturing a harness accomplishing the foregoing objects I have found that a smaller amount of webbing and fewer adapters are required than in the present standard harnesses and, therefore, the present invention may be said to have for an

object the production of an improved harness at a lower cost than heretofore.

In the case of harnesses used with seat packs it is customary to sew the downwardly extending portions of the lifting webs to the back straps to keep them from flapping, the stitching being sufficiently weak to rupture when the parachute opens. In accordance with another feature of my invention I provide a simpler method of holding the lifting webs of a seat pack in place and at the same time add to the comfort of the wearer of the harness and pack.

The various features of novelty whereby my invention is characterized will herein-after be pointed out with particularity in the claims; but, for a full understanding of my invention and of its objects and advantages, reference may be had to the following detailed description taken in connection with the accompanying drawing, wherein:

Figures 1 and 2 are respectively front and rear perspective views of a person wearing my improved harness; Fig. 3 is a view, partly in edge elevation and partly in section, showing fragments of one of the lifting webs, the corresponding breast strap, and one of the diagonal back straps, at their juncture; and Fig. 4 is a section along the edge of one of the back straps, at the point where the back straps cross.

Referring to the drawing, 1 and 2 are two lifting or suspension webs connected by a cross element 3, all being preferably made in one continuous length; the whole constituting a swing in which the rider sits, the part 3 forming the seat strap and the parts 1 and 2 extending upward in front of the wearer. There are two diagonal back straps, 4 and 5, crossing each other; each back strap extending forward at the top and lower end so as to pass over a shoulder of the wearer and over the hip on the opposite side. The breast strap device consists of two straps, 6 and 7, each fastened at its ends to one of the upright elements of the swing at the shoulder and at the hip. The distance along the straps, 6 and 7, between the fastenings at the ends, is greater than the corresponding distance along the upright swing elements, so that

when the breast straps are connected together at the middle, by means of a ring 8 and a snap hook 9, as shown in Fig. 1, each forms with a portion of one of the suspending webs a flat triangle. The upper forward end of each back strap is connected to one of the suspending webs at the shoulder. In the arrangement shown, this is accomplished by 5 slideable adapters each in the form of a metal frame-like part 10 having a cross bar 11; each suspending web and the upper part of the corresponding breast strap extending through one of the windows in the adapter; and the upper end of the corresponding back 10 strap being passed up from below through the adapter in contact with the rear side of the upper end of the breast strap, over the cross bar, down through the second window, in the adapter, and then back again to the 15 back of the harness along the upper side of the main portion of the back strap. The end of the back-turned part of the back strap is fastened to one bar of a second frame-like adapter 12 having a cross bar 13; the body 20 portion of the back strap being threaded through the adapter, passing through the first window, over the cross bar, and back through the second window.

The adapters 10 may be moved up and 30 down along the suspending webs, whereas the adapters 12 may be slid along the body portions of the back straps, varying the points of connection between the webs and the straps and the effective lengths of the straps.

35 The lower ends of the back straps are brought forward across the hips and are there connected to the suspending webs, as indicated at 14. The lower ends of the back straps may conveniently form parts of adjustable leg strap devices. In the arrangement shown, there are two leg straps 15 and 16 each fastened at one end to the seat strap 3. The free ends of each leg strap is 40 adjustably connected to one of the suspending webs by means of a ring 17 and a snap hook 18, one of which is slidably engaged with the adjacent portion of the corresponding back strap which is drawn into a loop or sling whose length may be varied to suit 45 the size of the thigh of the wearer. The length of this loop or sling depends upon the amount of back strap that is paid out at the lower end.

50 It will therefore be seen that the adjustments for the back straps and the leg straps are all made by simply shifting the adapters 10 and 12; no separate adjustment being required for the leg straps, as a pull on a back strap, in adjusting it, is transmitted to the corresponding leg strap which will be automatically tightened to the same degree. The harness is therefore not only simple in construction, but it may be easily adjusted to fit 55 any wearer in such a way that the pull will

be equalized between the back straps and the leg straps.

It will also be seen that at no time is there any tendency to pull the seat strap from under the rider, because the suspending webs are in front and, whatever pull there is on the leg straps is in a direction to draw the seat strap forward against the person of the rider. In case a person should fall backward or head down the lifting pull exercised by the suspending webs serves to tighten on the back straps and also the breast straps, so that there is no danger of falling out of the harness.

When the wearer sits down some slack appears in the suspending webs, between the shoulders and the hips; so that the harness, although safely tight when the wearer is standing, will be comfortably loose while the wearer is seated.

The amount of webbing required in the construction is considerably less than that in present types of commercial harnesses and, therefore, and because of the fact that no separate adapters are required for the leg straps, 90 the harness costs less to make. Each breast strap and one of the back straps may be and preferably are made from a single length of webbing which is suitably folded at the junction of the back strap with the suspending web to start the first leg of the breast strap in the right direction. Therefore the cost of manufacture as well as the cost of material is reduced to a minimum.

95 The upper ends of the suspending webs are carried back over the shoulders to the parachute pack, as is usual. When a seat pack is used a pad 19 may be placed in front of the back straps so as to lie between them and the back of the wearer. The lengths of the suspending webs extending down from the shoulders to the seat pack may then be fastened to this pad by quickly detachable fasteners to avoid the necessity of sewing them temporarily to the back straps. In the arrangement shown, the webs pass under little 100 tapes 20 each sewed at one end to the pad and detachably connected therewith at the other end by a snap fastener 21. These tapes hold the webs against the pad until a sufficient outward pull is exerted on the webs to release the snap fasteners, as is the case when the parachute opens and the weight of the rider 105 comes on the tapes.

110 While I have illustrated and described with particularity only a single preferred form of my invention, I do not desire to be limited to the exact structural details thus illustrated and described; but intend to cover all forms and arrangements which come within the definitions of my invention constituting the appended claims.

115 I claim:—

120 1. A harness comprising a swing in which the wearer is adapted to be seated with the 125

upright elements extending upwardly in front of him, diagonal back straps each adapted to extend forwardly over a shoulder of the wearer and over the hip at the opposite side, a member slidable along each of said upright

5 elements, the upper portion of each back strap extending slidably through the corresponding slidable member and being continued to the back along the strap, a sliding 70 connection between the lower end of the back-turned part of each back strap and the body of the strap, the lower and forward ends of the back straps being connected to said upright elements, two leg straps extending from 75 the bottom of the swing to the said upright elements near the lower ends of the latter, and a breast strap device detachably connecting said upright elements together.

2. A harness comprising a swing in which 20 the wearer is adapted to be seated with the upright elements extending upwardly in front of him, diagonal back straps each adapted to extend forwardly over a shoulder of the wearer and over the hip at the opposite 25 side, a member slidable along each of said upright elements, the upper portion of each back strap extending slidably through the corresponding slidable member and being continued to the back along the strap, a sliding 30 connection between the lower end of the back-turned part of each back strap and the body 90 of the strap, the lower and forward ends of the back straps being connected to said upright elements, two leg straps each secured 35 at one end to the bottom of the swing, slidable connections between the other end of each leg strap and the lower forward portion of the corresponding back strap, and a breast 40 strap device connecting said upright elements together.

3. A harness comprising a swing in which the wearer is adapted to sit with the upright elements of the swing lying in front of him, diagonal back straps each adapted to extend 45 forwardly over a shoulder of the wearer at the upper end and over the hip on the opposite side of the wearer at the lower end, connections between the upper and lower forward ends of each back strap and the adjacent 50 upright element, means to adjust the effective lengths of the back straps, leg straps extending forward from the bottom of the swing, means connecting each leg strap to the corresponding lower forward portion of the 55 corresponding back straps at variable distances from the corresponding upright element of the swing to cause variable lengths of the back strap adjacent to the said upright elements to be folded back and serve as 60 extensions of the leg straps, and a breast strap device between said upright elements.

4. A harness comprising a swing to the upright elements of which the parachute is adapted to be attached, in which swing the 65 wearer is adapted to sit with the vertical

swing elements lying in front of him, diagonal lengthwise-adjustable back straps adapted to extend forwardly over the shoulders and hips of the wearer to said vertical elements, connections between the back straps and said upright elements at the shoulders, leg straps each connected at one end to the bottom of the swing, connections between each upright, the corresponding leg strap and the lower forward end of the corresponding back strap to produce a leg-receiving loop of variable size, and a breast connection between said upright elements. 70

5. A harness comprising a swing to the upright elements of which the parachute is adapted to be attached, in which swing the wearer is adapted to sit with the vertical swing elements lying in front of him, diagonal lengthwise-adjustable back straps adapted to extend forwardly over the shoulders and hips of the wearer to said vertical elements, adjustable connections between the back straps and said upright elements at the shoulders, leg straps each connected at one end to the bottom of the swing, connections between each upright, the corresponding leg strap and the lower forward end of the corresponding back strap to produce a leg-receiving loop of variable size, and a breast connection between said upright elements. 80

6. In a harness, vertical suspension elements adapted to lie in front of the wearer of the harness, breast strap devices including two straps secured to the suspension elements at the shoulder portions and extending downwardly in converging relation to each other, metal adapters fitting around and slidable along the suspension elements and the upper portions of said breast straps, 100 back and leg strap devices including diagonal back straps adapted to extend forwardly over the shoulders of the wearer, each back strap passing through one of the aforesaid adapters and then backward along the 105 body portion of the back strap, and an adapter fastened to each of the back-turned ends of the back straps and slidably engaged with the body portion of the corresponding back strap. 110

7. In a harness, suspending members adapted to lie in front of the wearer, diagonal back straps, slides on said suspending members at the shoulders, the upper end of each back strap extending through the corresponding slide and folded back upon itself, and an adjustable connection between the free end of the back-turned portion of each back strap and the body portion of such strap. 115

8. In a harness, suspending members adapted to lie in front of the wearer, slides on the suspending members at the shoulders, diagonal back straps, slides on the back straps at the back of the wearer, the upper 120 125 130
